UNITED STATES PATENT OFFICE.

JOSEFA CASANOVAS VDA DE TOS, OF BUENOS AIRES, ARGENTINA.

INVOLVABLE AND UNFILLABLE BOTTLE.

Application filed December 29, 1926. Serial No. 157,882.

This invention relates to improvements in unrefillable bottles and has for its object to improve and simplify devices of this character and render them practical and efficient 5 in use.

Fig. 1 is a longitudinal sectional view of a bottle provided with the unrefillable device.

Fig. 2 is a sectional detail of the bottle cap removed.

Fig. 3 is a detail partly in section showing several of the parts of the unrefillable device detached.

Fig. 4 is a top plan view of the guard removed.

Referring to the drawing in detail the body 12^a of the bottle may be of the conventional or any desired form, while the neck portion 20 thereof is provided with an internal annular flange 21 constituting a seat for the unrefillable device. Outwardly of the flange 21 the neck portion 20 is provided with an internal annular groove 12 defining an internal annular shoulder facing the bottom or closed end of the bottle.

The unrefillable device includes a body composed of two parts designated at 2 and 3, the outer part 2 having a flanged and threaded outer terminal adapted to be closed by a removable cap 1 in which is fitted a cork insert 11. The inner terminal of the body part 2 is internally threaded and the correspondingly externally threaded adjacent terminal of the part 3 is fitted therein.

Normally diverging springs 8 are fastened to the body part 2 and are provided with angular terminals 8^a. During introduction of the body in the neck of the body the springs 8 are compressed and when the angular terminals 8^a thereof reach the other wall of the groove 12 they spring outwardly thereby locking the body against withdrawal.

A cork ring 10 snugly fitting about the terminal of the body part 3 is confined between the latter and the inner surface of the neck 20 and, with the terminal of the body part 3, abuts the stop flange 21 thereby limiting the inward movement of the body.

The external ring portion 9 of the guard 4 is clamped between the parts 2 and 3 and is provided with openings *a* through which the liquid passes during dispensation of the contents of the bottle. The enlarged middle portion of the body is provided with an outwardly flaring rim portion 4^a overlying the

opening *a* to prevent the introduction of implements intended for use in the unauthorized refilling of the bottle.

A guide 7 is confined between the shoulder 21 and the body part 3 and receives one terminal of a valve stem 6^a, the opposite end of which is received within a raised portion provided in the central portion of the guard 4. Adjacent its inner end the body part 3 is provided with an annular flange defining a valve seat 13 coacting with a valve 6 fixed to the stem 6^a, the latter moving by gravity with the stem 6^a to close passage through the seat 13 when the bottle is in an upright position. A float member 5 is located on the stem 6^a outwardly of the valve 6 and a spring 14 of 70 comparatively small tension is confined between the guard 4 and the float member 5.

The flange 4^a prevents the introduction of implements intended to affect the unauthorized unseating of the valve 6 for the purpose 75 of the unauthorized refilling of the bottle and the valve 6, in the upright position of the bottle, is maintained in closed position by gravity, assisted by the tension of the spring 14. However, when the bottle is inverted to 80 dispense its contents the weight of the valve 6 and float 5, together with the weight and pressure of the contents of the bottle, unseats the valve 6, thus permitting dispensation of the liquid.

Any attempt to refill the bottle with the latter in an inverted position is prevented owing to the action of the float 5, which rising with the incoming liquid and assisted by the spring 14 closes the valve 6, and thereby 90 prevents the introduction of liquid.

I declare to claim as my exclusive right:

1. An unrefillable closure for bottles, including a two-part hollow body, the parts of the body being abutting portions, an annular member interposed and held between the abutting parts of the body, a valve seat carried by one of the body parts, a valve located between the seat and the annular member, said annular member having openings therein for the passage of liquid, and a guard member carried by the annular member having an outwardly flaring rim portion overlying the openings in the annular member.

2. A device as claimed in claim 1, characterized by the provision of a guide carried by the first mentioned body part, a stem carried by said valve and movable in said guide,

said annular member having an aperture therein constituting a second guide for said stem.

3. A device as claimed in claim 1, characterized by the provision of a guide carried by the first mentioned body part, a stem carried by said valve and movable in said guide, said annular member having an aperture

therein constituting a second guide for said stem, and spring means interposed between the annular member and valve normally tending to close the latter.

In testimony whereof she has affixed her signature.

JOSEFA CASANOVAS BOADA vda de TOS.
